UNITED STATES PATENT OFFICE.

JOSEPH LEWIS MILLS, OF BALDWIN'S GARDENS, GRAY'S INN ROAD, COUNTY OF MIDDLESEX, ENGLAND.

APPARATUS FOR ENGRAVING.

SPECIFICATION forming part of Letters Patent No. 429,280, dated June 3, 1890.

Application filed January 3, 1889. Serial No. 295,360. (No model.) Patented in England July 16, 1888, No. 10,295; in France January 16, 1889, No. 195,416, and in Belgium January 18, 1889, No. 84,670.

To all whom it may concern:

Be it known that I, JOSEPH LEWIS MILLS, a subject of the Queen of the United Kingdom of Great Britain and Ireland, residing at Baldwin's Gardens, Gray's Inn Road, in the county of Middlesex, in that part of the United Kingdom aforesaid called England, have invented a certain new and useful Instrument or Apparatus for Engraving and Mezzotinting, whereby currents of compressed air or steam and sand are controlled by the hand and utilized for engraving and mezzotinting purposes; and I do hereby declare the following to be a full, clear, and exact description of the invention, which will enable others skilled in the art to which it appertains to make and use the same, reference being had to the accompanying drawings, which form part of this specification.

The above-mentioned invention has not been patented in any country except the following: England, No. 10,295, July 16, 1888; France, No. 195,416, January 16, 1889; Belgium, No. 84,670, January 18, 1889.

Figure 1 represents a side elevation of one form of the instrument embodying my invention, and Fig. 2 represents another form thereof.

In said drawings, *a* designates the air or steam tube, which is formed of any suitable metal or material furnished with a removable nozzle or point *b*, and attached by an india-rubber or other suitable pipe or tube *c* to an air-pump or steam-engine. This air-tube, as shown in Fig. 1, is placed parallel to a sand-tube *c*, formed of any suitable metal or material, attached to a reservoir for sand or such like by an india-rubber or other suitable pipe or tube *c*, and furnished with a removable nozzle or point *b*', and with a thumb-lever *h*, working on a pivot *i*, which lever, when depressed, opens the air-valve *j*. The spring *k* acts upon the aforesaid thumb-lever *h* and keeps the aforesaid air-valve closed. The ring *l* is loosely attached to the tube *a* for the first finger of the operator to enable the instrument to be suspended from his hand, and thus to leave his thumb free to act upon the aforesaid lever *h*.

The object of each of the nozzles or points hereinbefore mentioned being removable is, that it may be replaced by another nozzle more or less fine, according to the requirements of the work in hand. The said tubes *a* and *c* are designed for and fitted at their ends with ferrules or rings for the attachment of the india-rubber or other suitable pipes or tubes for the conveyance of compressed air or steam and sand or such like, respectively, to said tubes *a* and *c*.

In the form of my invention shown in Fig. 2 the tube *a*, formed of any suitable metal or material, is attached to an air-pump or steam-engine by an india-rubber or other suitable pipe or tube *c* and furnished with a removable nozzle or point *b*. It is attached by metal brackets *c*, *c*' to the sand-tube *c*', which is furnished with a removable nozzle or point *b*', and is attached to the reservoir for sand or such like by an india-rubber or other suitable pipe or tube *c*', which is punctured over and hither throughout its entire length by very fine holes, sufficient for the admission of air from the outside, but insufficient to permit the escape of sand or such like from said pipe or tube *c*'. The aforesaid pipe or tube *c*' is of a composite character, being made up of sections or parts of brass or other suitable metal or material, which vary in capacity, and of two hollow globes or balls, of which the upper or larger *b*' is glass, the lower and smaller *b* of copper or other suitable metal or material. Some of these sections or parts contain a pipe or tube of porcelain or enamel to facilitate the passage of the sand or such like through the said tube *c*'. The globes or balls *b*' and *b* are punctured over and hither by very fine holes, sufficient to admit air from the outside, but insufficient to permit the escape of sand or such like from the inside thereof, and in the top and bottom of each of said globes or balls and in a vertical line a circular hole or orifice is made, which hole or orifice corresponds in circumference to the circumference of the particular section or part to which said globe or ball is attached by solder, cement, or other convenient medium. The object of puncturing the pipe or tube *c*'

- and interposing the punctured globes or balls b^2 and b'' between the aforesaid sections or parts is to prevent the sand-tube c^2 becoming congested by the sand or such like falling from the reservoir for sand and so forming a vacuum, which would impede the free flow of the sand or such like through said tube c^2 in its passage to the nozzle or point b' .
- 5 The operation is as follows: The nozzles b and b' being in proximity, the jet of air or steam issuing from the former will strike the sand falling or propelled through the other nozzle and drive it against the surface on which it is to operate. These nozzles may be 10 moved about by hand and directed on the points which require such treatment. This instrument is especially designed to be used in my process described in application Serial No. 303,040, filed March 12, 1889. The said application describes my instrument herein set forth and claimed, but does not claim it.
- Having now fully described and ascertained the nature of my said invention and in what manner the same in its several modifications 15 is to be carried into practice, I claim—
1. In an instrument for applying sand or other abrading substance, a tube a , a nozzle b thereon, a flexible pipe connecting said tube with a source of air-supply, and a sand- 20 tube having a nozzle arranged in juxtaposition to the nozzle b aforesaid outside of said nozzle b , in order that the sand issuing therefrom may be struck by the blast of air at an angle as it issues from nozzle b and caused to impinge on the surface to be abraded, substantially as set forth. 35
2. The sand-tube c^2 , provided with perforated bulbs b'' b'' , in combination with the pipe connecting said tube with the sand-reservoir, the nozzle b' of said sand-tube, and an air-blast pipe having a nozzle arranged to discharge against the sand issuing from the nozzle of said sand-pipe, substantially as set forth. 40
3. A perforated pipe c' , leading from the sand-reservoir, in combination with the sand-tube to which it is attached, a nozzle on said sand-tube, tube a , provided with a nozzle discharging against the sand issuing from the nozzle of said sand-pipe, and a flexible pipe connecting said tube a with a source of air-supply, substantially as set forth. 45
4. The sand-tube c^2 and air-tube a , in combination with their nozzles, their supply-pipes, and the bars or braces c^3 c^4 , which connect them and hold their nozzles in juxtaposition, substantially as set forth. 50
- In testimony whereof I have hereunto put my hand this 10th day of October, 1888.
- JOSEPH LEWIS MILLS.
